UNITED STATES PATENT OFFICE.

CHARLES MORRILL, OF NEW YORK, N. Y.

FASTENER FOR THE MEETING-RAILS OF SASHES.

SPECIFICATION forming part of Letters Patent No. 284,046, dated August 28, 1883.

Application filed July 13, 1882. (No model.)

To all whom it may concern:

Be it known that I, CHARLES MORRILL, of New York city, have invented certain new and useful Improvements in Sash-Locks, of 5 which the following is a specification.

My invention relates to that class of sash-locks in which the pivoted or swinging button or lock-bar on the upper sash is provided with a retractile bolt or catch to engage with the 10 plate on the lower sash when swung into engagement therewith, so as to prevent the unlocking movement of the lock-bar, except by first releasing the catch from the inside of the house.

15 It also relates to those sash-locks in which the lock-bar is pivoted on a horizontal axis and arranged to swing vertically up and down over the joint of the meeting sashes.

20 My improvements aim to provide a sash-lock of this type which, while being very secure, will be simple in construction and less expensive to manufacture than those heretofore; and my improvement chiefly relates to the manner of producing the retractile catch 25 or burglar-proof engagement between the lock-bar and the hook or plate on the lower sash; and this may be stated to consist in pivoting the lock-bar to a lug which has a hinged or pivoted connection to the base-plate on the 30 upper sash, with a spring to constantly pull said lug down upon the base, whereby the lock-bar is allowed to spring or yield forward when swung down into its locking position, and thus permit a latch-tooth on the lock-bar to ride over 35 and snap into engagement with a hook or latch on the lower sash, which thereby locks the two in secure burglar-proof engagement.

My invention also consists in details of construction relating to the latching or locking 40 teeth, and also to the hinging-lug and lock-bar, whereby the lock-bar is held firmly in its upright or unlocked position when so placed, to prevent the lock-bar from falling over against the raised sash, as hereinafter fully 45 set forth.

In the annexed drawings, Figure 1 is a plan view of my improved sash-lock shown in its locked position. Fig. 2 is a sectional end elevation shown in the unlocked position. Fig. 50 3 is a front elevation in the same position. Fig. 4 is a sectional front elevation of the

parts affixed to the upper sash. Fig. 5 is a plan view of the hinging-lug removed; Fig. 6, a vertical section thereof on x x ; Fig. 7, a perspective view of the same. 55

In Figs. 1, 2, 3, and 4, b indicates the top bar of the lower sash, and a the bottom bar of the upper sash.

d indicates the base-plate of that part of the sash-lock which is affixed to the lower sash, 60 and c the base-plate of the part affixed to the upper sash.

e indicates the lock-bar, button, or lever of the sash-lock, which bar is mounted on the base-plate c of the upper sash, and is pivoted 65 on a horizontal axis-pin, f , so as to swing vertically down over the meeting joint of the sashes upon the base-plate d of the lower sash, as shown by full lines in Fig. 1 and indicated by dotted lines in Fig. 2. The lock-bar is 70 not pivoted directly to the base-plate, but to a hinging-lug, g , which has a hinged or pivoted connection with the base-plate, as will hereinafter appear, and the pivotal end of the lock-bar is forked or cleft, as seen best in Figs. 75 1, 3, and 4, to straddle the lug, as shown, and the base of the cleft is indented or notched to form a latching-shoulder or lock-tooth, h , which, when the lock-bar is swung down into its locking position, will engage with an arrow-head or latching-hook, i , projecting from 80 the base-plate d of the lower sash, in coincidence with the cleft in the pivotal end of the bar, as will be readily understood from Figs. 1, 2, and 3. Now, the hinging-lug g is 85 formed with a base-flange, k , to rest on the base-plate c , and with an underlying central tongue, l , which passes through a slot across the middle of the base-plate (see Figs. 2 and 4) and projects within the hollow of the base-plate, as shown. Through the front end of the 90 tongue l is passed a pin, m , which underlies the base-plate, and the front edge of the base-flange k , above the base-plate, is rounded off, as best shown in Figs. 2 and 7. The lug g has hence 95 a pivotal or hinged connection with the base-plate, and while it is prevented from becoming bodily raised up or detached from the base by means of the pin m , it can yet rock slightly forward or backward on the rounded edge k , 100 as will be understood. The back end of the tongue is perforated with a short slot, through

which is passed a bow or leaf spring, *n*, whose ends bear on the under side of the hollow base-plate *c*, and thus constantly tend to hold the hinging-lug in its quiescent position, with its base-flange *k* seated firmly on the base-plate *c*, as shown in Figs. 1, 2, 4, and 6.

Referring now to Fig. 2, it will be seen that if the lock-bar *e* be swung down while the hinging-lug is in its quiescent position, the 10 are through which the lock-tooth *h* moves will intersect the inclined face of the latch-hook *i*, and the two will thus come into opposing contact. If, however, the lock-bar be pressed firmly downward, or if it be pulled 15 slightly forward, the hinging-lug *g* will yield forward slightly, and thus permit the lock-tooth *h* to ride easily over the inclined face of the hook *i* till the hook arrives at the barb or engaging-notch of the hook, when the two will then spring 20 into secure engagement by the reaction of the spring *n* on the hinged lug *g*, as will be readily understood, thereby causing the two parts of the sash-lock to become so engaged that they cannot become burglariously unlocked by 25 any implements inserted between the sashes. When, however, the inmates of the house desire to unlock the sashes, this can be readily done by first pulling the lock-bar *e* forward slightly and then raising it up into the position shown 30 in Fig. 2, when both sashes may then be readily moved up or down.

It will be noted on reference to Figs. 1, 2, 3, and 4 that the tip of the latch-hook *i* is tapered or beveled, so that it will readily enter the 35 slot of the lock-bar *e* when the latter is swung down into its locking position, although the hook and the slot may be slightly out of line with each other.

If desired, the sides of the slot may be tapered, instead of the top or sides of the latch-hook, with equivalent effect, as will be understood, and it will be readily seen that by this 40 means not only will the lock-bar engage with the hook easily, even if out of line, but in thus engaging with the hook it will at the same time bring the two parts of the sash-lock and the two sashes into their true central or relative positions, which is a very desirable feature in the operation of the lock.

Now, a minor feature of my invention consists in means to hold the lock-bar in its raised 50 position, as seen in Fig. 2, when thus placed, so as to prevent its falling over against the lower sash, and thus becoming jammed between the sashes.

Referring to Figs. 2, 5, 6, and 7, it will be seen that slots *o* are formed through the base-flange *k* of the hinging-lug *g* close on either side of the lug, which slots admit the tines or branches of the forked pivotal end of the lock-bar *e*, as seen in Figs. 2 and 4. Now, the front and lower corner of these tines is rounded off to a circular curve struck from the pivot center *f* and tangent to the surface of the base *c*, (see Fig. 2,) while the remainder of the end of the tines is tangent to said circle and coincident

to the surface of the base. It will hence be readily seen that the rounded concentric corner on the pivotal end of the lock-bar will allow the lock-bar to swing down freely into its locked 70 position when so forced; but when swung into its raised position, as seen in Fig. 2, the flat or tangent end of the lock-bar will coincide with the flat surface of the base, and will be held close thereto by the retraction of the hinging-lug *g*, thus holding the lock-bar firmly in its upright position, somewhat similar to the manner in which the blade of a pocket-knife is held when opened.

It will be noted of course that the tangent 80 end of the lock-bar should not be exactly at right angles to the upright sides of the bar, but at a slight inclination, so as to allow the lock-bar to incline backward when raised, and thus bring the center of gravity of the lock-bar on that side of the axis on which the spring *n* acts to hold it, as will be understood.

It will be noted that knobs *r*, of ornate pyramidal shape, are fixed on each end of the pivot-pin *f* and project from each side of the 90 lock-bar, and thus impart an attractive ornamental finish to the bar; and it will be also noted that the bar in front or plan view is designed in an ornamental cruciform shape, which greatly improves the appearance of the 95 sash-lock. These ornamental qualities of the construction or design I reserve, however, for the subject of a design patent.

As shown best in Fig. 2, I prefer to form the hook *i* separate from the base-plate *a*, but with 100 a shank, which is inserted in a slot in the base, and there rigidly held by riveting the end of the shank, or by the pins *s*, as illustrated. It will therefore be readily noted that by the construction described both base-plates *c* *d* 105 are formed separately from their attachments and without any protuberances, so that the surface of the base-plates, when cast, may be finished off smooth and bright, and the attachments *i* *g* afterward affixed thereto, which 110 will be less expensive in the manufacture and allow a better finish.

Any other equivalent and elastic or forwardly-yielding connection of the lock-bar *e* with the base-plate besides that shown may 115 be adopted, and any other form of engaging latch-teeth *h* *i* may be substituted for those shown without departing from the principle of the invention.

Any novel feature which I may have shown 120 but not claimed in this application I reserve for the subject of a future application.

What I here claim as my invention is—

1. In a sash-lock, the combination, with a lock-bar arranged to swing over the joint of 125 the meeting sashes, of a forwardly-yielding lug to which the lock-bar is pivoted, and which is hinged to one sash, with a projecting hook affixed to the other sash, and an engaging latch hook or shoulder on the lock-bar to engage therewith, substantially as and for the 130 purpose set forth.

2. In a sash-lock, the combination, with an affixing base-plate, *c*, adapted to be affixed to the upper sash, of a hinging-lug, *g*, pivotally and elastically connected with said base, the lock-bar *e*, pivoted to said lug and provided with a catch-notch or shoulder with a hook, *i*, adapted to be fixed to the lower sash to engage with said bar, substantially as herein shown and described.

10 3. The combination, with a base, *c*, of the

hinging-lug *g*, pivotally engaged thereto, the spring *n*, engaged with the lug and bearing on the base, and the lock-bar *e*, pivoted to the lug, substantially as and for the purpose set forth.
